UNITED STATES PATENT OFFICE.

STEPHEN CHASE HOUGHTON, OF PACIFIC GROVE, CALIFORNIA, ASSIGNOR OF ONE-HALF
TO JAMES E. BEAN, OF SAN JOSE, CALIFORNIA

RAILWAY-SIGNAL FOR GRADE-CROSSINGS.

1,295,033.

Specification of Letters Patent. Patented Feb. 18, 1919.

Application filed February 18, 1917. Serial No. 148,439.

To all whom it may concern:

Be it known that I, STEPHEN CHASE HOUGHTON, a citizen of the United States, residing at Pacific Grove, in the county of 5 Monterey and State of California, have invented certain new and useful Improvements in Railway-Signals for Grade-Crossings, of which the following is a specification.

10 My invention relates to the class of railway-signals adapted for use particularly at grade-crossings.

The value and efficiency of a warning signal depend essentially upon and are in proportion to their impressiveness, that is to say, the force with which they compel attention. But other factors enter into the problem, as, for example, simplicity in construction, resulting in economy in manufacture and certainty in operation or use. It will readily be understood, therefore, that a signal involving moving parts, no matter how well it may compel attention, may be so complex that its operation is uncertain 25 and its construction faulty and liable to derangement necessitating frequent adjustment and repair, so that its employment therefore may be attended with prohibitive expense.

30 The object of my invention is to avoid these objections by providing a fixed or non-movable signal of simple construction, but adapted, by its general form and the now universal education of the public with respect to its warning character, to, not only attract attention, but also, by reason of its improved structure, to more forcibly than ever before compel said attention. To this end my invention consists in the novel signal which I shall now fully describe by reference to the accompanying drawings, in which—

Figure 1 is a front elevation of my signal, partly in section.

45 Fig. 2 is a side elevation, partly in section, on the line 2—2 of Fig. 1.

Fig. 3 is a cross section on the line 3—3 of Fig. 1.

50 Fig. 4 is an end view of one of the arms, the dotted lines showing the construction lying under the cap.

Fig. 5 is a diagrammatic view of the automatic electric control of the signal light.

55 The signal essentially comprises a cruci-

form structure indicated generally by A, and a central-light structure, represented by B.

The cruciform structure is, in its best form, composed of four radial arms subtending right angles, and so suspended by two of its arms from a bar C, that it hangs vertically and each arm meets a central horizontal plane at an acute angle. Thus the device intentionally presents the form of the now universally accepted and well known conventional upright cruciform warning railway signal at grade crossings.

It must be understood that the entire signal may, in detail be constructed in any suitable manner, and that in describing its construction as here illustrated, I am disclosing merely the preferred details.

The sides of the arms, using the word "sides" in contradistinction to fronts or faces, are composed of a single continuous strip 1 of sheet-metal, which beginning at any given point, say the extremity of one arm, thence extends radially to a central drum 2, to which it conforms and is secured at 60 3, and thence extends radially from said drum to the extremity of a second arm, at which it is bent at right angles to form the end of said arm; thence inwardly again to the drum 2 to which it is again secured, 65 thus completing said second arm; thence outwardly once more to the extremity of the third arm, and bent at right angles, and thence inwardly to the drum, thus completing the third arm, and so forth to form 90 the fourth arm, and after completing the first arm, reaches the line of beginning.

Referring now particularly to Fig. 3, it will be seen that the edges of the strip 1 are bent lineally to form grooves 1' and by 95 reference to Figs. 4 and 2, it will be further seen that the strip at its right angles ends is cut out at 4 on each side.

Into these openings 4 and grooves 1' are slipped the sheets or panes 5 of translucent material, in practice white opalescent glass, which form the faces of the arms and thus convert said arms into chambered or hollow closures. The glass panes are held in place by caps 6 which cover the ends of the arms, 105 the caps being removably held in place by short bolts 7.

The central drum 2 has openings 2' into the inner ends of the hollow arms.

Carried by a bracket 8 secured to the in- 110

ner ends of the two upper arms and depending in the drum is an electric lamp 9, from which run the wires 10 of an electric circuit. This circuit is adapted in the manner usual with warning lights of this general character, to be closed and opened automatically by the approach and recession of a train to and from the neighborhood of the signal. For example as shown in Fig. 10 a simple arrangement may be as follows: 20 indicates a section of a railway track, having at 21, the insulated rail-joints. The rails have a circuit 22 including a track battery 23 and a relay 24 with a switch 25 armature 25 to which is connected the wire 10 leading to the light 9 of the signal structure A. The other member 26 of the switch is connected with a battery 27 which by the wire 10 is included in the signal light circuit. 20 The car wheels while on the track-section 20 shunt the track battery 23 which causes the relay 24 to drop the armature 25 onto the switch member 26 thereby completing the crossing signal light circuit. 25 When the car leaves the track section, the track battery 23 energizes the relay and opens the signal light circuit.

11 is a hood, one on each side. The outer portion of the hood is of an inverted U-shape, as shown in Fig. 1, and is open at its outer end, so that the rays of light may be seen both through its end and bottom thereby attracting attention from a distance and from below it nearer by. The inner end of the hood is cylindrical and is inwardly flanged at 12, Fig. 2, to form a seat for the lens 13. There is a lens on each side, and they are red ones, thereby giving the usual and conventional warning red light, and by reason of the hood, this light is visible also by day.

The lens is held in place by a slip ring 14 in the hood.

The hood 11 on one side is removably fitted to the drum by means of a slip sleeve 15 secured to its exterior and fitted to the drum ends, being held in place by the screws 16.

The signal is suspended from the bar C by means of hangers 17 secured to the two upper arms, the bar passing through the hangers and confined by cotter pins 18. The bar C with its signal may be carried by any suitable support, and it may be located in any desired position. Its best location is directly above the roadway and in the middle thereof, and in this position it may be carried by its bar C clamped to an overhanging arm of a side post or clamped to 60 a cross cable extending between posts on each side of the roadway. As these form no part of my invention, I have not deemed it necessary to illustrate such supports and positions as these are well known. At the 65 ends of the arms I have shown air vents 19.

It will now be seen that in my device there are combined essentially the conventional vertically disposed cruciform warning arms of a railway crossing signal and the conventional red-light danger signal. 70 Both are conspicuous day and night. In the day time the white translucent faces of the arms and the hooded red light in the center are both objects which compel attention. At night, the rays of the lamp 75 entering the hollow arms illuminate their translucent opalescent glass panes with a whiteness most effective visually, and the red rays transmitted by the lenses are equally effective. Both are warnings to 80 which the public has long been educated, and their increased effect, due to their union in one device, their relative arrangement, and their inherent conspicuousness, renders the device as a whole a simple, effective and durable warning for the purpose intended.

I claim:

1. A railway-signal comprising a vertically disposed cruciform structure with immovable arms; a danger signal light at the intersection of said arms; and means for effecting the automatic control of said light to indicate the approach and passage of a train. 95

2. A railway-signal comprising hollow radially directed warning arms, the functional faces of which are translucent; a drum centrally disposed with relation to said arms and having openings in its periphery into the cavities thereof; and a danger signal light within the drum some of the rays of said light being visible through the ends of the drum and other rays thereof illuminating the translucent faces of the 100 arms through the openings in the drum periphery.

3. A railway-signal comprising hollow radially directed warning arms, the functional faces of which are translucent; a 110 drum centrally disposed with relation to said arms and having openings in its periphery into the cavities thereof; a light within the drum, some of the rays of which illuminate the translucent faces of the arms; 115 and red lenses in the drum for converting the remaining rays of the light into a danger signal visible through the ends of the drum.

4. A railway-signal comprising hollow 120 radially directed warning arms, the functional faces of which are translucent; a drum centrally disposed with relation to said arms and having openings in its periphery into the cavities thereof; a light 125 within the drum, some of the rays of which illuminate the translucent faces of the arms; red lenses in the drum for converting the remaining rays of the light into a danger signal visible through the ends of the drum, 130

and open ended hoods projecting outwardly from said lenses.

5. A railway-signal comprising hollow radially directed warning arms, the functional faces of which are translucent; a drum centrally disposed with relation to said arms and having openings in its periphery into the cavities thereof; a light within the drum, some of the rays of which 10 illuminate the translucent faces of the arms; red lenses in the drum for converting the remaining rays of the light into a danger signal visible through the ends of the drum, and open ended hoods projecting outwardly from said lenses, said hoods being also open 15 in their lower portion.

In testimony whereof I have signed my name to this specification in the presence of two subscribing witnesses.

STEPHEN CHASE HOUGHTON.
